UNITED STATES PATENT OFFICE.

SAMUEL M. VAUCLAIN, OF PHILADELPHIA, PENNSYLVANIA.

RELIEF-VALVE FOR LOCOMOTIVES.

SPECIFICATION forming part of Letters Patent No. 657,472, dated September 4, 1900.

Application filed June 30, 1900. Serial No. 22,120. (No model.)

To all whom it may concern:

Be it known that I, SAMUEL M. VAUCLAIN, a citizen of the United States, residing in Philadelphia, Pennsylvania, have invented certain 5 Improvements in Relief-Valves for Locomotives, of which the following is a specification.

The object of my invention is to prevent the formation of a partial vacuum in the low-pressure cylinder of a compound engine and the passages leading thereto and to prevent the accumulation of steam in the low-pressure cylinder, due to a leaky throttle. This object I attain by coupling a pipe to the central 10 chamber of the valve and mounting a relief-valve in this pipe.

The figure in the accompanying drawing is a sectional view of sufficient of a piston-valve and its chest to illustrate my invention.

20 In the present instance, A is the cylindrical valve-chamber, having a bushing a.

B is the high-pressure cylinder, and C is the low-pressure cylinder.

E is the central exhaust-port. H represents 25 the ports leading to the high-pressure cylinder B, one on each side of the central exhaust-port, and L L are the ports leading to the low-pressure cylinder C. These ports are between the high-pressure ports and the steam-ports at 30 the end. It will be understood, however, that in some instances the exhaust-ports may be at the end and steam may enter through a central port.

The piston-valve D has a head d at each 35 end and two rings d' between the two heads. Between each head d and a ring d' are passages f f, which form communication at one side with the low or the high pressure ports and on the other side with the high and low 40 pressure ports. The center f' of the valve is hollow, forming communication between the passages f f, so that when the valve is in the position shown in the figure the steam will pass from the high-pressure port on one side 45 to the low-pressure port on the opposite side. The central annular groove g in the piston between the two rings d' d' forms a communication between the exhaust-port and through one of the ports L, leading from the low-pressure 50 cylinder.

When the valve is in the position shown in the drawing, the left-hand end of the high-

pressure cylinder is taking steam through the steam-inlet port S at the left-hand end of the valve-chamber and the left-hand port H and 55 steam is exhausting from the opposite end of said cylinder through the hollow valve to the left-hand port L of the low-pressure cylinder, the opposite end of the low-pressure cylinder exhausting through the channel formed by 60 the groove g in the valve to the exhaust-passage E.

D' is the valve-rod, connected in the ordinary manner to the valve-operating mechanism, and in order to balance the valve I extend from the rear of the valve a tubular stem 65 D². This stem passes through the packing-box a' in the head of the valve-chest. The tubular stem D² extends through the valve D in the present instance and is a continuation 70 of the valve-rod D', although in some instances it may be a stem independent of the valve-rod. I perforate the stem at d², as shown, and provide a back-pressure relief-valve I at the end of the stem. In the present 75 instance this valve I rests on a projection i, cast on an elbow D³, screwed into the stem D². Screwed into the upper portion of the elbow is a valve-seat I', having a central stem i', on which is screwed a cap i². 85

When the valve is at rest, the normal position is open, it resting upon the projection i', as shown in the drawing; but as soon as steam is admitted to the valve the pressure of steam will immediately close the valve 85 against its seat and hold it there during the normal working of the engine.

By my invention the locomotive can drift without creating a vacuum in the low-pressure cylinder or the passages leading thereto, 90 as when steam is cut off the check-valve will open and air will be drawn through the hollow stem into the central portion f' of the valve-chamber. This construction will prevent locomotives from starting owing to leaky 95 throttles, as the steam as it slowly escapes will pass through the hollow stem D² and around the valve I.

I claim as my invention—

1. The combination of the cylinders of a 100 compound engine, a hollow valve controlling the flow of steam to and from the said cylinders, a hollow stem communicating with the passage in the valve, and a relief-valve in

this tubular stem closing against steam-pressure, substantially as described.

2. The combination of the cylinders of a compound engine, a valve-chamber communicating with the said cylinders, a piston-valve in said chamber controlling the passage of steam to and from said cylinders, said valve having a central passage forming a communication between one end of one cylinder and the opposite end of the other cylinder, a hollow stem secured to the valve and communicating with the said central passage, and a valve in said stem closing against steam-pressure, substantially as described.
- 15 3. The combination of the high and low pressure cylinders, a valve-chamber communicating with both cylinders, a hollow piston-valve therein having a central passage communicating with the ports leading to the ends 20 of the said cylinders, a hollow stem extending into the valve from the rear and perfo-

rated, said stem extending through a packing-box in the valve-casing, and a valve closing against steam-pressure, said valve being mounted on the stem, substantially as de- 25 scribed.

4. The combination of a hollow piston-valve, a stem extending from the rear of said valve, the portion of the stem within the valve being perforated, an elbow secured to 30 the end of the stem, a valve-seat secured in said elbow, a valve mounted in the elbow and closing against the seat under steam-pressure, substantially as described.

In testimony whereof I have signed my 35 name to this specification in the presence of two subscribing witnesses.

SAMUEL M. VAUCLAIN.
